GURNEY ELECTRIC ELEVATOR COMPANY, OF HONESDALE, PENNSYLVANIA, A
CORPORATION OF PENNSYLVANIA.

ELEVATOR SAFETY DEVICE.

1,102,246.

Specification of Letters Patent.

Patented July 7, 1914.

Continuation of application Serial No. 559,303, filed May 4, 1910. This application filed July 12, 1911.
Serial No. 638,187.

To all whom it may concern:

Be it known that I, ANDREW M. COYLE, a citizen of the United States, and a resident of the borough of Manhattan, in the city, county, and State of New York, United States of America, have invented certain new and useful Improvements in Elevator Safety Devices, of which the following is a specification.

10 My invention relates to elevator safety devices or clutches such as are used to lock elevator-cars to the guides over which they run. Its object is to improve upon such apparatus and to provide a simple mechanism 15 of this kind which cannot be subjected to severe strains and by means of which the car may be brought to rest gradually but positively. This and other objects of my invention will appear in the following specification in which I will describe my invention, and the novel features of which I will set forth in the appended claims.

This application is a continuation of a former application for patent Serial No. 25 559,303 filed May 4, 1910.

Referring to the drawings, Figure 1 is a bottom plan view of an elevator safety device made according to my invention, with the rails with which it is arranged to engage 30 shown in section. Fig. 2 is a side elevation, partly in section, of the same device. In Fig. 3 I have shown some of the parts of this device in sectional end elevation, the section being taken on the line 3—3 of Fig. 1. 35 Fig. 4 shows a detail of construction, this figure illustrating the connection between one of the weighted arms and the actuating shaft of the safety. Fig. 5 is a diagrammatic representation of the manner in 40 which this device, when on an elevator, is connected with an actuating governor.

Like characters of reference designate corresponding parts in all of the figures.

10 designates a portion of an elevator-car, 45 and 11 its hoisting cable.

12, 12 are guides over which the car travels.

Under the floor of the car is my novel safety device, which comprises a pair of 50 channel irons 20, 20, the ends of which are riveted to the upright channels 21 which form a part of the frame of the car.

22 are brackets secured to the channels 20

near their ends. These brackets support vertical pins 23 each of which serves as a pivot 55 for a pair of clamping jaws 24, 25. The outer portions of these jaws are arranged to engage with and to be forced upon the guides 12. On the other side of the pivots they are carried in toward the center of the 60 car, and carry, near their inner ends, anti-friction rollers 26 and 27. The inner portions of these jaws are so constructed that they form guide-frames for wedges 28 which lie between them and which, when moved 65 toward each other, act against the rollers 26 and 27 to force the jaws onto the guides by forcing their inner ends apart. The manner in which this operation takes place will be more specifically set forth hereinafter. 70

30 is a shaft which is rotatably supported in links 31, which are swung from a supporting shaft 32, passing through the channel-irons 20. A yoke 33, which is rigidly affixed to the shaft 30, is connected by links 75 29 with both of the wedges 28. The shaft 30 projects beyond one of the channel-irons 20, and this projecting end is threaded as is shown at 34. A drum 35 is loosely mounted upon the smooth portion of this projecting 80 part of the shaft, but is provided with arms 36 which engage a threaded block 37 on the threaded portion of the shaft in such a way as to cause the block to rotate with the drum, and to have a longitudinal movement on the 85 shaft at the same time.

38 is a spring surrounding the shaft and interposed between the drum and the threaded block.

39 designates a friction disk rigidly affixed 90 to shaft 30 and arranged to engage with a friction surface on the face of the drum 35.

40 is an arm affixed to the shaft 30. This arm carries on its outer end a heavy weight 95 41. A pin 42 projecting from one side of this arm is engaged by a latch 43 which is loosely pivoted upon a shaft 44, which is rotatably supported by bearings on the channel-irons 20. The latch 43 has a releasing arm 45 which extends into a position near 100 the seat of the inner flange of the drum 35. On this seat of the drum flange is a shoulder 46 which is arranged to engage with the releasing arm 45. 47 is a rod connected with this releasing arm which may be carried 105 up to such a position that it may be actuated

by an operator in the car. 50 designates another arm which carries on its outer end a heavy weight 51. This arm is not directly affixed to the shaft 30 but between it and the shaft is a collar 52. This collar is affixed to the shaft and has projecting from it a lug 53. The hub of the arm 50 is loosely mounted upon this collar and is cut away to clear the lug 53 so that the shaft and collar may have a certain amount of movement without affecting the arm 50.

10 A pin 54, projecting from one side of the arm 50, is engaged by a latch 55 which is affixed to one end of the shaft 44. Its releasing arm 56 is also affixed to shaft 44 in such a position as to cause it to be engaged by a shoulder 57 projecting from the outer side of the drum flange. These shoulders are affixed at different circumferential positions. A releasing rod 58 is also connected with the releasing arm 56.

15 On the inner side of the drum 35 is a bevel gear 60 which may be an integral part of the drum, or it may be a separate member affixed thereto. A pinion 61 is in mesh with this gear. The spindle to which this pinion is affixed is designated by 62. Its upper end is squared off so that it may be turned by a socket-wrench through the floor 20 of the car 10. This spindle may be supported by a bracket 63 which has a bearing on the end of the supporting shaft 32 and another on the shaft 30, so that with the links 31 it helps to support the shaft 30.

25 In Fig. 5 one of the ways of actuating this safety device is shown. In this figure 70 designates a centrifugal governor. An endless rope 71, running over the governor sheave 72 is connected with the car 10 by 30 means of a light yieldable leaf spring 73 so that the governor will be driven by the movement of the car. 73 is a weighted sheave in the lower loop of the governor rope which serves the purpose of keeping 35 it taut and in driving engagement with the governor sheave. The rotation thus imparted to the governor has a tendency to throw the balls 74 outward and this will raise a rod 75 against the action of a weight 40 76 thereon. As soon as the speed of the car and the governor exceed a predetermined amount this will throw a clamp 77 into engagement with the governor rope and will lock it against further movement. 78 is another rope one end of which is secured to 45 the drum 35 around which it is given several convolutions. Its other end is then carried under a sheave 14 on the car and up to the point 79 on the governor rope to which 50 it is securely attached. After the governor rope has been thus locked a further movement of the car will first release the spring connection between the car and the governor rope and will then cause a pull to be exerted 55 upon the rope 78. The latter will then be

unwound from the drum 35, causing it to rotate. This part of the operation is common practice and is well-known in the art. Now as soon as the drum 35 is rotated the shoulder 46 will be brought into engagement with the releasing arm 45 and will cause the latch 43 to be removed from the pin 42. The weighted arm 40 will then drop causing a partial rotation of the shaft 30, which, through its connection with the wedges 28, 28, will cause them to be drawn together between the antifriction rollers which will force the jaws 24, 25 against the guides 12. Thus a positive braking force will be immediately applied to the car as soon as the rotation of the drum 35 commences. The swinging support of the shaft 30 equalizes the pressure which the two wedges produce on their respective pairs of jaws. The lost motion connection between the shaft 30 and the weighted arm 50 permits this slight rotation of the shaft without affecting the arm 50. If the braking effect thus produced is not sufficient to stop the car a further rotation of the drum 35 will bring the shoulder 57 into engagement with the releasing arm 56 and will move the latch 55 away from the pin 54. This will let the weighted arm 50 drop and it will have a tendency to further rotate the shaft 30 and to force the jaws more tightly on the guides. A spring or other buffer 59 may be interposed between the arm 50 and the collar 52 if desired to avoid jarring when the lost motion between these parts is taken up.

55 I will now describe the further operation of this device if the car still continues its movement. The rotation of the drum 35 has been moving the threaded block 37 in 105 against the spring 38, and these parts are so set that they become effective to press the friction surface of the drum against the friction disk 39 at about the time the weighted arm 50 is released. The drum will then have 110 a tendency to rotate the shaft 30 with it to still further tighten the locking jaws. The compression of the spring 38 is continually increasing and consequently the slippage between the drum and the friction disk is decreasing. This is of importance because it causes the car to be brought to rest gradually but more especially because of the fact that it prevents any undue strain being put upon the ropes 71 and 78, as is the case in the 115 arrangements now in use. It is to be noted that through the connections with the rods 47 and 58, the operator in the car may release either or both of the weighted arms at will and may thus retard or stop the car 120 in an emergency. The spindle 62 is provided so that the safety device may be reset after it has been operated. It may be seen that by it the drum may be rotated in the opposite direction to that imparted to it by 125 130

the rope 78. This will wind up the rope 78 and will push the threaded block 37 back until a lug on the back of it engages with a lug on a stop 30^A secured to the threaded portion of the shaft 30, after which the shaft will be rotated with the sheave. Then the jaws will be released, and both of the weighted arms will be raised and latched, and the device reset with its parts in their initial positions.

What I claim is:—

1. In an elevator safety device, a pair of locking jaws, mechanism for forcibly moving said jaws toward each other, said mechanism comprising a plurality of weights for actuating said mechanism, and means for successively releasing said weights.

2. In an elevator safety device, a pair of locking jaws, mechanism for forcibly moving said jaws toward each other, said mechanism comprising a plurality of weights arranged to actuate said mechanism, and a rotatable member, said member being arranged to successively release the weights and to act upon said jaws cumulatively with the weights.

3. In an elevator safety device, a pair of locking jaws, a cam for forcibly moving said jaws toward each other, a weighted arm arranged to move the cam, and a rotary member arranged to release the weighted arm and to impart further movement to the cam.

4. In an elevator safety device, a pair of locking jaws, a cam for forcibly moving said jaws toward each other, a weighted arm arranged to move the cam, and manual means for releasing said weighted arm.

5. In an elevator safety device, a pair of locking jaws, a cam for forcibly moving said jaws toward each other, a weighted arm arranged to move the cam, a rotary member arranged to automatically release the weighted arm, and manual means for releasing the weighted arm.

45 6. In an elevator-safety device, a pair of locking jaws, a cam for forcibly moving said jaws toward each other, a plurality of weighted arms arranged to move the cam, and manual means for releasing one or more of said arms.

55 7. An elevator-car, a safety device therefore, said device comprising a pair of locking jaws, a cam for forcibly moving said jaws toward each other, a plurality of weighted arms, each arranged to move the cam, means for automatically releasing said weighted arms successively, and means manually operable from the car for releasing one or more of said arms.

60 8. In an elevator safety device, two pairs of locking-jaws, a cam for each pair of jaws for forcing the jaws of each pair toward each other, said cams having linear paths of movement, a rotatable actuating shaft, at 65 right-angles to the path of movement of the

cams, eccentric connections between the shaft and the cams, and a swinging support for said shaft.

9. An elevator-car, a safety device therefore, said device comprising a pair of locking-⁷⁰ jaws, mechanism for forcibly moving said jaws toward each other, said mechanism comprising a plurality of weights arranged to actuate said mechanism, and a rotatable member, said member being arranged to successively release the weights and to act upon said jaws cumulatively with the weights; and means manually operable from the car for resetting the weights and the rotatable member.

80 10. An elevator-car, a safety device therefore, said device comprising a pair of locking-jaws, a cam for forcibly moving said jaws toward each other, a plurality of weighted arms each arranged to move the cam, a rotatable member arranged to automatically release said arms successively, and means manually operable from the car for resetting the weights and the rotatable member.

85 11. In an elevator safety device, a pair of locking-jaws, means for forcibly moving said jaws toward each other, said means comprising a rotatable member, a frictional connection between the jaws and said member, and means for causing the pressure at 95 said frictional connection to be progressively varied by the rotation of said member.

100 12. In an elevator safety device, a pair of pivoted locking-jaws, a cam for forcibly moving said jaws toward each other, a rotatable sheave for moving the cam, a frictional connection between the sheave and the cam, and means for causing the pressure at said frictional connection to be progressively increased by the rotation of said sheave.

105 13. In an elevator safety device, a pair of pivoted locking jaws, a cam for forcibly moving said jaws toward each other, a weighted arm arranged to actuate said cam, a rotatable sheave arranged to release said 110 arm, a frictional connection between the cam and said member whereby the rotation of said member may also move the cam, and means for causing the pressure at said frictional connection to be increased by the rotation of said sheave.

115 14. In an elevator safety device, a pair of pivoted locking-jaws, a cam for forcibly moving said jaws toward each other, a plurality of weighted arms each arranged to move the cam, to 120 move said cam, a rotatable sheave arranged to successively release said weighted arms, a frictional connection between the cam and said sheave whereby the sheave may also move the cam, and means for causing the pressure at said frictional connection to be increased by the rotation of the sheave.

125 15. In an elevator safety device, two pairs of pivoted locking-jaws, a cam for each pair of jaws for forcing the jaws of each pair to- 130

ward each other, said cams having linear paths of movement, a rotatable actuating shaft at right-angles to the path of movement of the cams, eccentric connections between the shaft and the cams, and a swinging support for said shaft; a plurality of weighted arms on the actuating shaft each arranged to actuate said shaft, a rotatable sheave loosely mounted on the shaft, said 10 sheave being arranged to successively release said weighted arms, a frictional connection between the sheave and the actuating shaft

whereby the sheave may also actuate the shaft, and means for causing the pressure of said frictional connection to be increased by 15 the rotation of said member.

In testimony whereof I have signed my name to this specification in the presence of two subscribing witnesses.

ANDREW M. COYLE.
